FRITZ SCHRÖTER, OF BERLIN, GERMANY, ASSIGNOR TO GESELLSCHAFT FÜR
DRAHTLOSE TELEGRAPHIE M. B. H., OF BERLIN, GERMANY

PICTURE TRANSMISSION

Application filed February 23, 1929, Serial No. 342,059, and in Germany March 3, 1928.

The present invention relates to picture transmission and is particularly directed to radio transmission of pictures, although, of course, it is possible to use the scheme for 5 wire line or wired radio systems.

The object of the present invention is to produce a method and apparatus for transmitting pictures in which the detrimental effects of the fading phenomena during operation are substantially eliminated, and this result has been accomplished, in the present instance, by continually altering the transmitted wave.

According to the present invention, the 15 transmitted wave is changed as to its frequency in the short time interval between the exploration and scanning of any two successive lines on a picture which is to be transmitted. It is, of course, possible, and also 20 within the spirit and scope of the invention, to make this shift in frequency even during the transmission of any one line of the picture without waiting until the completion of any particular line of scanning, should 25 conditions where this is necessary arise. However, the invention will be described only in connection with the former of the two above disclosed methods, since a system will readily suggest itself to anyone skilled 30 in the art to which the invention relates by which the modified form of frequency shift may be accomplished.

Other objects of the invention will, of course, at once become apparent from a reading of the following specification and claims 35 when considered together with the accompanying drawing in which a single figure thereof illustrates one form which my invention may assume although, it is to be understood, that certain modifications and changes 40 may be made thereto provided they fall within the spirit and scope of the hereinafter appended claims.

The means, as shown by the drawing, for 45 accomplishing the objects of the invention may consist, for instance, in the use of a revolving contact which is coupled with the scanning device or associated with the picture carrying drum and whose positions actuate the element whereby the frequency of the

transmitted wave is altered in the time interval between the exploration of any two successive picture lines. Of course, it is possible to change the frequency in many ways, for example, by causing the contact to change 55 the connection and flow of a direct current, or, perhaps, break the flow of a direct current which serves to magnetize an iron core choke coil with the result that the inductance thereof is influenced or changed. The said contact may also be used to connect or disconnect a driving mechanism for a condenser and, as has been shown in the present instance, a change in frequency by way of an increase or a decrease thereof may also be 60 accomplished under certain conditions by the short circuiting of a resistance member.

By such automatically produced changes 65 in frequency the picture lines scanned in sequence may be transmitted at different frequencies and since the fading phenomena manifests this but rarely on two different frequencies in the same manner it is possible to improve the quality and efficiency of transmission by making use of two distinct frequencies. 70

In so far as the use of the hereinafter described method, and the arrangement to be adopted at the receiving end, are concerned, automatic changes in the receiving apparatus must be effected broadly in accordance 80 with changes in the transmission wave length. For instance, in the case of heterodyne reception the locally generated wave should suitably be so changed that the same beat 85 frequency will always be preserved. However, it is also possible to work without any alterations of the heterodyne frequency by adjusting the heterodyne to a frequency 90 which is equal to the frequency of the longer wave minus half the difference between the two transmission waves or the frequency of the shorter wave plus half the difference between the two transmitted waves. In this case the same differential note will be obtained by both transmission waves while the heterodyne remains unvaried. 95

If the transmission takes place on two waves which are widely separated from each other then, under certain conditions, it may 100

be necessary to change the tuning conditions at the receiving end in accordance with the changes in the wave length at the transmission end. In such cases, of course, the receiving arrangement must be so chosen and adapted that the changes in tuning are effected in synchronism with the changes in the wave length at the transmitting end. As has been above pointed out, however, if the changes in the transmitted wave length are small it is possible to leave the receiving apparatus unchanged, but whether or not the receiving apparatus is changed or unchanged will depend largely upon working conditions, which are different for each case.

Now referring more particularly to the drawing accompanying this description, a showing of one exemplification of the idea embodying this invention, it has been presupposed that the carrier frequency in relation to the receiver is little changed so that the special measures described for changing the receiver may be dispensed with in this case.

As shown by the accompanying drawing, the picture drum 1 carries the picture to be transmitted and for the purpose of concrete illustration of one embodiment of the invention a reflection type of transmitter using opaque or semi-opaque pictures has been shown. This picture carrying drum is driven from a synchronous motor of any desired type or characteristics, which is maintained by any well known scheme in synchronism with a like element at the transmitter. For convenience of illustration this synchronous motor has not been illustrated.

As shown by the drawing, the angle α designates the portion of the picture drum which is free from the picture elements. It is this portion of the picture drum which serves for securing the picture to the drum and by the present invention this is the portion of the picture carrying drum whose passage time before the scanning element is to be utilized in order to vary the wave length of the transmitter.

The photo cell 2, which is preferably of the annular type for a reflection type transmitter, is arranged adjacent the picture carrying drum 1 for the purpose of scanning the picture. Light from a source 3 is projected through a small diaphragm 4' and lens 4 to produce a point image of the luminous source 3 upon the surface of the picture drum. For the purpose of producing the picture current carrier wave for amplification a perforated light chopper disk 5 has been provided. In accordance with the present illustration separate motor 6 has been shown for the purpose of driving this perforated light chopper disk.

Associated with the picture drum 1 is a commutating arrangement 7 which, through an appropriate speed reduction or driving

gear mechanism, is so arranged as to run at one half the speed of the picture carrying drum 1. The commutator 7 has half of its circumference covered by a conducting segment 8, while the remaining part of the commutator is an insulating segment. A circuit through the battery 11 can be made through the electromagnet 10 by way of the sliding contact 9 only when the commutator is so turned that the contact 9 passes over the conducting segment 8 but while contact 9 rests on the insulating portion of the commutator there is an open circuit in this path.

The change from the current interruption period (as shown by the drawing) to the current flow period by way of the contact 9 takes place at the instant when the angle α passes through the scanning zone in front of the photo cell 2. This action is utilized for the purpose of influencing the transmitter as follows: When current flows from the battery 11 through the electromagnet 10, the contact 9, the conducting segment 8 and back to ground, a relay or switch 12 is closed and in this manner a portion of a resistance 13 connected in series with a direct current generator 15 is short circuited. This results in a change in the anode potential upon a vacuum tube 16 acting across the terminals of resistor 14.

The tube 16 is so arranged as to act as a crystal controlled generator. The tube arrangement 16 comprises an oscillatory circuit consisting of parallelly connected inductance 17 and capacity 18 and in addition a tickler or regeneration coil 19 and a control or master crystal 20 made from quartz.

It has been found, to be sure, that the wave length of the oscillation circuit is kept at a constant value inside relatively narrow bounds by the aid of the crystal 20 but that inside the said interval it is liable to be acted upon by variations of the anode potential on the oscillator 16 with a result that according to whether the relay or switch 12 is closed or open a somewhat changed control frequency will be produced. This frequency will be altered from one line of the picture carried by the drum 1 to the next in accordance with the arrangement hereinbefore disclosed.

As shown by the drawing the energy from the oscillator 16 is amplified by means of an amplifier 21 and is then directed to a modulator 22 which is also supplied with current variations from the photo cell 2 which are first amplified in an amplifier 24 of well known characteristics or type. The output of the modulator 22 is then directed to a transmitter 23 of any desired type and is transmitted by means of the antenna system 24.

Instead of a change in the carrier wave at the sending end, an intermediate modulation wave, if used, could be altered, for also in this manner the alteration in the carrier frequency will be insured automatically. For

instance, the scanning disk note could be varied, if such a disk is used at the sending end of the system.

Having now described my invention, what I claim is:

- 5 1. In a picture transmission system, means for scanning and analyzing a picture for transmission, means for modulating a transmitted wave in accordance with the point for point intensities of light and shade on the transmitted picture, and means for continually changing the frequency of the transmitted carrier at the period between any two successive line for line scannings of said picture.
- 10 2. In a picture transmission system, a rotatable picture supporting element, means for scanning a picture to be transmitted, means for producing a plurality of individual carrier frequencies, means for modulating said carrier frequencies in accordance with the varying point for point tone intensities on the said picture, and means operable from said picture supporting element for alternately changing from one to the other of said carrier frequencies at predetermined time intervals during the scanning of a plurality of lines of said picture.
- 15 3. In a picture transmission system, means for scanning a picture to be transmitted, means for producing a plurality of individual carrier frequencies, means for modulating said carrier frequencies in accordance with the varying point for point tone intensities on the said picture, and means for alternately changing from one to the other of said carrier frequencies at the end of each successive line for line scanning of said picture.
- 20 4. In a picture transmission system, a picture supporting element, means for illuminating elemental areas of the picture carried by said supporting element, means for producing a relative movement between said illuminating means and the said supporting element for successively scanning the picture along a plurality of adjacent paths, means for generating a carrier frequency for transmitting the picture, means for modulating said carrier frequency in accordance with the intensity of light and shadow on elemental areas of the said picture, and means operable at predetermined points in the scanning of the supported picture determinable by pre-established points in the relative movement between the picture support and illuminating means for varying the carrier frequency within predetermined limits.
- 25 5. In a picture transmitting system, a rotatable picture supporting element, means for scanning a picture carried by said supporting element, a generator for generating carrier frequencies for transmission, a resistor element in said generator circuit, means operable from said picture supporting element for varying the value of the resistance in said

generator circuit at the end of each line of scanning of the said picture for changing the frequency of transmission, and means for modulating each of the controlled generated carrier frequencies in accordance with the intensity of light and shadow on elemental areas of the picture.

6. In a picture transmission system, a vacuum tube oscillator for generating carrier frequencies for transmission, means connected with said oscillator for changing the frequency thereof, a rotatable picture supporting and scanning means for analyzing a picture for transmission, relay means operable from said picture carrying element at a predetermined point in the rotation thereof for controlling said frequency varying means for varying the generated frequencies, and means for modulating each of the controlled generated frequencies of said oscillator in accordance with the intensity of light and shadow on elemental areas of said picture surface.
